UNITED STATES PATENT OFFICE.

FRED L. HOLMES, OF WAVERLY, MASSACHUSETTS.

TILTING FRAME FOR COOKING-STOVES.

SPECIFICATION forming part of Letters Patent No. 739,872, dated September 29, 1903.

Application filed December 3, 1902. Serial No. 133,670. (No model.)

To all whom it may concern:

Be it known that I, FRED L. HOLMES, a citizen of the United States, residing at Waverly, in the county of Middlesex and State of Massachusetts, have invented new and useful Improvements in Tilting Frames for Cooking-Stoves, of which the following is a specification.

This invention relates to improvements in cooking stoves or ranges, and has for its object to provide means whereby the two front lids and short center of the cooking-stove top may be simultaneously raised, so that coal or wood may be inserted in the fire-box of the range, and also the object of the invention is to raise said short center and lids simultaneously for the purpose of checking the draft and for broiling or toasting.

The invention consists in the combination and arrangement of parts set forth in the following specification and particularly pointed out in the claims thereof.

Referring to the drawings, Figure 1 is a plan view of my improved tilting frame, showing the same in connection with a portion of the top of an ordinary cooking-stove, with the front lids and short center of said cooking-stove supported upon said tilting frame. Fig. 2 is a plan view of a portion of the top of a cooking-stove constructed to receive my improved tilting frame, said tilting frame being removed therefrom. Fig. 3 is a plan view of the tilting frame. Fig. 3^a is a plan view of a modified form of tilting frame. Fig. 4 is a section taken on line 4-4 of Fig. 1. Fig. 5 is a section taken on line 5-5 of Fig. 1. Fig. 6 is a section similar to Fig. 4, illustrating the tilting frame raised in position to have fuel placed in the fire-box of the stove. Fig. 7 is a perspective view of a portion of the stove-top and a portion of the tilting frame, said tilting frame being shown raised, as in Fig. 6, and viewed from the front right-hand side of Fig. 1 looking in the direction of the arrow *a* in said figure. Fig. 8 is a perspective view of a portion of the top of the stove and of the tilting frame, said tilting frame being shown raised, as in Fig. 6, and viewed in the direction of the arrow *b*, Fig. 1. Fig. 9 is a perspective view of one corner of the tilting frame viewed in the direction of the arrow *c*,

Fig. 3. Fig. 10 is a perspective view of a portion of the top of the stove and the supporting-post therefor, the central portion of the tilting frame being illustrated as raised 55 upon the ledge of said supporting-post.

Like numerals refer to like parts throughout the several views of the drawings.

In the drawings, 11 is the top of an ordinary cooking-stove; 12, the fire-box thereof; 13 13, the end walls of said fire-box, and 14 and 15 the front and rear walls thereof, respectively.

16 is my improved tilting frame. Said tilting frame is provided with an aperture 17 to 65 receive the front lids 18 18 and the short center 19 of the stove. The said tilting frame 16 is provided with a flange 20, extending around it and projecting on the front and ends thereof above a flange 21, provided upon 70 the top of said stove. On the rear side of the tilting frame the flange 20 projects beneath a flange 22, provided upon the top of the stove.

A supporting-post 23 is provided adjacent to the rear wall 15 of the fire-box and located 75 immediately beneath the stove-top 11. Said supporting-post is provided upon the front face thereof with a laterally-extending ledge 24.

The tilting frame 16 is provided with a slot 80 25, extending inward upon the rear edge thereof midway between the two ends. Said slot engages the opposite sides of the supporting-post 23 when the tilting frame is raised, as in Figs. 6 and 10, and prevents said 85 tilting frame from moving longitudinally thereof. When the tilting frame is in the raised position aforesaid, the bottom of the slot 25 rests upon the top of the laterally-extending ledge 24, and the flange 20 at each 90 end of the tilting frame projects through a transverse slot 26, provided in the flange 21 at each end of the fire-box.

It will be noted that when the tilting frame is raised, resting upon the laterally-extending ledge 24 of the supporting-post 23, there is a space between the rear edge of the tilting frame and the top of the rear wall of the fire-box, so that the draft from the fire-box over the top of the oven will not be entirely 100 cut off. A stop 27 is provided upon each end of the tilting frame, which abuts against the

flange 21 at each end of the fire-box adjacent to the slot 26 when the tilting frame is drawn upwardly from its tilted position, as in Figs. 7 and 8, preparatory to dropping said tilting frame into its normal position, as in Figs. 1 and 4. These stops 27 act as a guide to the user, so that he may know to what extent to draw said tilting frame upwardly before dropping the same into its normal position.

10 A handle 28 is provided upon the front edge of the tilting frame, extending forwardly therefrom, said handle being provided with a slot 29, extending therethrough and forming a convenient means for the insertion of a poker or lifter in case said handle should be hot.

The operation of my improved tilting frame for cooking-stoves is as follows: Assuming the tilting frame to be in the position shown 20 in Figs. 1 and 4 with the lids and short center in position, said frame is lifted at an angle from the position shown in Figs. 1 and 4 to approximately the position shown in Figs. 6, 7, 8, and 10 by means of the handle 28. It is then 25 allowed to slide downwardly until the bottom of the slot 25 rests upon the laterally-extending ledge 24, and the flange 20 at each end of the tilting frame projects through the slots 26 in the flange 21 at each end of the fire-box 30 of the stove and rests against said flange and against said supporting-post. Coal or wood may now be readily put into the fire-box of the stove without removing the lids 18 18 and short center 19, or if it is desired to check the 35 draft the tilting frame may be lifted to its raised position. To return said tilting frame, lids, and short center to the normal position, (indicated in Figs. 1 and 4,) said tilting frame is drawn forwardly and upwardly until the 40 stops 27 abut against the flanges 21 on the stove-top at each end of the fire-box. Said tilting frame is then allowed to descend to a horizontal position, as shown in Figs. 1 and 4, with the flange 20 at the rear edge of the 45 tilting frame supported upon the top of the post 23, it being noted that a portion of the top of said supporting-post extends forwardly in advance of the top of the stove. In addition to the convenience of being able to insert fuel without removing the lids it is evident with the tilting frame and lids in the position shown in Fig. 6 that broiling or toasting may be readily and conveniently performed. It is evident that the short center 50 19, hereinbefore referred to and described, may be cast integral with the tilting frame, and in Fig. 3^a I have illustrated this form of my device, in which 30 is the tilting frame, 31 31 apertures for the lids, and 32 the handle. The tilting frame illustrated in Fig. 3^a, 55 with the exception hereinbefore noted—viz., that the short center is cast integral with the frame—is in all respects a duplicate of the tilting frame illustrated in Fig. 3 and is operated in precisely the same manner as here-

inbefore described with relation to said tilting frame illustrated in Fig. 3.

Having thus described my invention, what I claim, and desire by Letters Patent to secure, is—

1. In a cooking-stove, a tilting frame provided with apertures to receive the two front lids of said stove, together with a slot in the rear edge of said tilting frame adapted to engage a supporting-post located adjacent to the rear wall of the fire-box and beneath the top of said stove. 75

2. In a cooking-stove, a tilting frame provided with apertures to receive the two front lids of said stove, and a flange upon the top of said stove projecting inwardly therefrom beneath one end of said tilting frame, said flange provided with a transverse slot to receive one end of said tilting frame and hold the same at an angle to the top of said stove. 80

3. In a cooking-stove, a tilting frame provided with apertures to receive the two front lids of said stove, a flange upon the top of said stove projecting inwardly therefrom beneath one end of said tilting frame, said flange 90 provided with a transverse slot to receive one end of said tilting frame and hold the same at an angle to the top of said stove, and a stop fast to one end of said tilting frame and adapted to abut against said flange for the purpose 95 specified.

4. In a cooking-stove, a tilting frame provided with apertures to receive the two front lids of said stove, and a supporting-post located beneath the top of said stove adjacent to the rear wall of the fire-box and provided with a laterally-extending ledge for the purpose specified. 100

5. In a cooking-stove, a supporting-post located beneath the top of said stove adjacent to the rear wall of the fire-box thereof and provided with a laterally-extending ledge, and a tilting frame provided with apertures to receive the two front lids of said stove, together with a slot in the rear edge of said tilting frame adapted to engage said post and rest upon said ledge. 105

6. In a cooking-stove, a tilting frame provided with apertures to receive the two front lids of said stove, a flange upon the top of said stove projecting inwardly therefrom beneath one end of said tilting frame, said flange provided with a transverse slot to receive one end of said tilting frame and hold the same at an angle to the top of said stove, and a stop fast to one end of said tilting frame and arranged to abut against the flange upon said stove for the purpose specified. 115

In testimony whereof I have hereunto set my hand in presence of two subscribing witnesses. 125

FRED L. HOLMES.
